UNITED STATES PATENT OFFICE.

ALBERT LEACH, OF CAMPOLLO, MASSACHUSETTS, ASSIGNOR, BY DIRECT AND MESNE ASSIGNMENTS, TO UNITED SHOE MACHINERY COMPANY, OF PATERSON, NEW JERSEY, A CORPORATION OF NEW JERSEY.

NEEDLE-GUIDE.

942,919.

Specification of Letters Patent. Patented Dec. 14, 1909.

Application filed December 29, 1906. Serial No. 349,998.

To all whom it may concern:

Be it known that I, ALBERT LEACH, a citizen of the United States, residing at Campollo, in the county of Plymouth and State 5 of Massachusetts, have invented certain new and useful Improvements in Needle-Guides; and I do hereby declare the following to be a full, clear, and exact description of the invention, such as will enable others skilled 10 in the art to which it appertains to make and use the same.

The present invention relates to needle guides for sewing machines and more particularly to needle guides for leather sewing 15 machines.

The invention is designed primarily for use on shoe sewing machines which employ a curved hook needle although it is also capable of use on other types of leather 20 sewing machines.

In the operation of shoe sewing machines the frictional contact of the leather with the needle causes the needle to become heated, and this heating of the needle bakes 25 the fine particles of leather and dust, which collect on the needle, into a hard scale. The scale which forms on the needle interferes with the movement of the needle through the needle guide and gives considerable 30 trouble to the operator, especially when a new needle guide which closely fits the needle is placed in the machine. As heretofore constructed the needle guide, especially when new, soon becomes clogged with 35 the scale so as to require frequent cleaning to cause the needle guide to operate properly or to avoid breaking the needle.

The object of the present invention is to provide a needle guide which will act to 40 remove the scale from the needle and which will not become clogged during the operation of the machine.

With this object in view the present invention contemplates providing the needle 45 guide with a cutting edge or edges adapted to remove the scale from the needle during the passage of the needle therethrough.

The invention contemplates forming the cutting edge or edges in any suitable manner 50 but it is preferred to form the cutting edge by cutting away the metal of the guide at the end of the perforation through which the needle passes so as to form a beveled surface along which the severed scale can pass

without any liability of clogging the guide. 55 The guide may be provided with a cutting edge at either or both ends of the perforation through which the needle passes and in the preferred form of the invention a slot is provided in the guide so as to divide the 60 perforated portion into two parts and a knife edge is provided at each end of the perforation in each of these parts.

The present invention will be clearly understood from an inspection of the accompanying drawing in which—

Figure 1 is a view in side elevation of so much of a well known sole sewing machine as is necessary to illustrate the connection of the present invention therewith. Fig. 2 is a 70 view in front elevation of the parts illustrated in Fig. 1, and Fig. 3 is a detail sectional view illustrating the perforated portion of the needle guide and the hook needle passing therethrough.

With the exception of the perforated portion of the needle guide the mechanism illustrated in Figs. 1 and 2 is constructed and arranged as in the sole sewing machine disclosed in the patent to French and Meyer, 80 No. 473,870, 1 indicating the work-support, 2 the awl, 3 the needle, and 4 the needle guide.

In the illustrated embodiment of the present invention the needle guide is provided with cutting edges 5, 6, 7 and 8, the cutting edges 5 and 8 being located at the front and rear sides of the guide respectively and completely surrounding the needle, and the cutting edges 6 and 7 being formed at the sides of a central slot which divide 90 the perforated portion of the guide into two parts, these cutting edges, as shown, extending only partly around the needle. To afford clearance for the scale removed from the needle by the cutting edges they 95 are formed, as best illustrated in Fig. 3, by cutting away the metal of the guide so as to form beveled surfaces sloping away from the needle. The cutting edges extend close to the surface of the needle and act effectively to remove any scale from the needle and to prevent the needle guide from becoming clogged. The provision of the cutting edges on the needle guide not only overcomes the difficulties which have heretofore been 100 experienced when a new needle guide has been placed in a machine but also permits the use of a needle guide provided with a

perforation which fits the needle snugly and accurately.

The nature and scope of the present invention having been indicated and the preferred form of the invention having been specifically described, what is claimed is:

1. A needle guide for sewing machines, provided with a cutting edge arranged to extend close to the surface of a needle and remove scale from the needle during the passage of the needle therethrough.
2. A needle guide for sewing machines, provided with a perforation through which the needle passes and having a cutting edge arranged to extend close to the surface of the needle and remove scale from the needle during the passage of the needle there-

through and formed by a bevel surface sloping away from the needle.

3. A needle guide for sewing machines 20 provided with a perforation to receive the needle, a slot dividing the perforated portion into two parts, and cutting edges at the ends of the perforation in each part arranged to extend close to the surface of the 25 needle and formed by bevel surfaces sloping away from the needle.

In testimony whereof I affix my signature, in presence of two witnesses.

ALBERT LEACH.
